UNITED STATES PATENT OFFICE.

EMILE PAULY, OF PARIS, FRANCE.

MEANS FOR MAKING HOLLOW-MONOLITHIC BUILDING ELEMENTS.

Application filed October 17, 1925, Serial No. 63,402, and in France October 22, 1924.

The present invention relates to an improved process and means for making hollow cement, concrete or reinforced concrete monolith building elements adapted to enter in the construction of walls, partitions, floors, roofs, columns or stanchions, and other parts of structures.

According to the present invention, the said elements are moulded in a mould of substantially gutter-like shape, which is provided with removable partitions and plates which may be fitted to the said mould in such a manner that the periphery of the transverse section of the moulded element shows at least a straight side and at most two sides constituted by arcs of a circle, the length of the element being adjustable at will by placing removable transverse partitions in the gutter-like mould, while the ends of the said elements may if desired be closed by forming them against removable end walls fitted to the mould.

An embodiment of the invention is, by way of example only, illustrated by the accompanying drawing, wherein:

Fig. 1 is a horizontal section of two walls at right angles to one another, built with the building elements according to the invention,

Fig. 2 is a partial perspective view of a mould according to the invention,

Figs. 3 and 4 are transverse sections showing various stages of the moulding operation, and

Figs. 5 and 6 are transverse sections showing the arrangement of the mould for obtaining modified shapes of the moulded element.

As previously explained, the hollow monolith element made according to the invention has a transverse section of which the periphery shows at least a straight side and at most two sides constituted by arcs of a circle.

Referring to Figure 1, the juxtaposed monolith element entering in the construction of the walls have a straight side 1 and a curved side 2, so that they have a half-cylindrical shape. At the edges, the elements are provided externally with two projecting ribs 3, provided for the purpose of leaving between the juxtaposed element spaces for receiving metal rods 4 encased in the cement or concrete which binds the elements and forms the solid portion of the wall 5. In order to reinforce the said ribs 3, rods 6 may be encased therein during moulding. A suitable reinforcement may also be placed

during moulding in the curved side 2 of the element.

The mould used to make the building elements according to the invention comprises a member 7 of gutter-like shape, made of sheet metal or other suitable material, suitably supported and maintained with its longitudinal edges upwards. The mesh work constitutes the reinforcement of the element being arranged in the gutter-like mould 7 so as to leave open the upper portion of the latter, the concrete, which should preferably be heated is supplied under pressure and suitably distributed by using a suitably made template. The length of the element obtained is determined by the spaces of transverse partitions 8 of which the ends 9 are removably hooked on the edges of the mould 7 as shown in Fig. 2. The whole of the curved portion of the element is thus obtained. In order to mould the flat upper portion of the element, removable supporting plates 12 (Figs. 3, 5 and 6) are placed on supporting rods removably supported in holes of the mould 7. The portions of the reinforcing meshwork projecting beyond the edges of the already moulded curved portion of the elements being folded onto the supporting plates 12, concrete is evenly distributed on the latter.

If it is desired to obtain elements closed at the ends, the partitions 8 (Fig. 2) are replaced by removable end plates of walls 13 (Fig. 4). These end plates 13 bear on the upper edges of the mould 7 and are maintained in a suitable position by means of supporting lugs 14 which leave open a portion of the inner cross section of the gutter-like mould corresponding to practically the whole of the cross section 2 of the element fitting the gutter. The end plates 13 being suitably positioned at the ends of the mould, concrete is applied against such end plates after arranging if desired a reinforcing meshwork. The concrete thus applied is connected to the periphery of the elements for practically the whole cross section of the latter, i. e. only with the exception of the portions of such cross section covered by the lugs 14, and the straight upper portion. The slits which are left in this manner are subsequently filled. It is obvious that the plates 12 must be removed before closing the two ends of the elements are closed. The removal of the plates 12 is effected by removing the rods 11, whereby the said plates 12 are allowed to drop and can

readily be taken out of the moulded section.

It will be obvious that the moulded elements may have another cross section than that shown in Fig. 1.

5 For instance, if a flat false bottom 16 is arranged in the gutter-like mould 7 so as to reduce the depth of the latter as shown in Fig. 5, an element will be obtained of which the cross section showing two straight sides 1 and 1^a, which may be parallel or non-parallel, and two curved sides 2 and 2^a.

10 By dividing the gutter-like mould 7 by a longitudinal vertical partition 15, as shown in Fig. 6, there may be obtained an element of 15 which the cross section shows two straight sides 1 and 1^a and a single curved side 2. Of course, in this last case, the end plates used when making elements having closed ends are 20 of a shape fitting the cross section of the moulded element.

Again, by fitting the gutter-like mould 7 both with a false bottom such as that shown

at 16 in Fig. 5 and a longitudinal vertical partition such as that shown at 15 Fig. 6, it would be possible to obtain an element of 25 a cross section showing three straight sides and a single curved side, and it is obvious that many other combinations are possible.

I claim:

An apparatus for molding monolithic construction elements, comprising in combination a mold of substantially gutter-like shape a portion of the element to be made therein fitting the inner wall of this mold, removable rods extending transversely across the wider portion of said mold, removable plates supported by said rods, these plates serving for forming on them the flat portion of said elements extending between the longitudinal edges of the said mold. 35

40 In testimony whereof I signed hereunto my name.

EMILE PAULY.
